AND RUDOLF LORENZ, OF RADZIONKAU, NEAR BEUTHEN, PRUSSIA,
GERMANY.

ROTARY AND OSCILLATING APPARATUS FOR DISTILLING METALLIC ORES.

SPECIFICATION forming part of Letters Patent No. 380,135, dated March 27, 1888.

Application filed November 24, 1885. Serial No. 183,838. (No model.)

To all whom it may concern:

Be it known that we, WILHELM RICHTER, of Eintrachthütte, near Schwientochlowitz, and RUDOLF LORENZ, of Radzionkau, near Beuthen, both in the Prussian Province of Upper Silesia, and German Empire, have invented certain new and useful Improvements in Rotating or Oscillating Apparatus for Distilling Zinc-Blende, Calamine, and other Metalliferous Ores, of which the following is a specification.

Our invention relates to an improved rotary oscillating apparatus for distilling metallic ores, and especially for distilling zinc-blende, calamine, or other zinciferous ore.

It consists of the particular constructions and combinations hereinafter described and particularly claimed.

Figure I is a longitudinal section, and Fig. 20 II a cross-section, of the apparatus on the line *a b* in Fig. I.

25 *e* is a cylindrical retort of fire-proof material, (chamotte,) which is supported by means of the ribs *f*, leaning against the cylindrical shell *a*, of refractory material, surrounding the said retort *e*, so that a space or chamber, *g*, is formed, from whence radially-arranged canals *h* extend, which lead off the fire gases which enter through the end pieces, I I I, from the generator and play around the retort within the space or chamber *g*.

30 The retort *e* is charged and emptied through the closable port *l* when the process of distillation is ended. For emptying the retort the port *l* is turned downward.

The shell *a* is clad with sheet-iron, to which the toothed ring is attached, which is operated by the toothed wheels *d*, so that the entire apparatus is set in rotary motion.

40 The rings *b*, which rotate on the rollers *C*, are connected to the toothed ring and serve to carry the entire apparatus.

When the apparatus rotates, the retort *e*, shell or chamber I I, forward end piece, *n*, and rear end piece, I I I, the condensing-chamber *o*, and the zinc-dust chamber *q* also rotate, while the ring *i*, surrounding the forward part of the apparatus, is stationary, so that the canals *h* rotate within the same. If, now, these canals

50 *h* come, during the rotation of the apparatus, in communication with the collecting-canals *k*, which can be closed by means of a suitable slide, *S*, they give off their products of combustion, which are led off into the open air or into a chimney.

55 The process is carried into operation in the following manner: If the retort has been charged through the port *l* with a charge of calamine and coal until the same is about half full, the port *l* is closed and the apparatus caused to make a rotary movement by means of appropriate gearing and toothed rings, while the fire-gases introduced from the rear through *m* play around the retort in the direction shown by the arrows. The contents of the retort *e* will, 60 in consequence of the rotation of the apparatus, roll on the walls of the said retort and thus produce a continuous mixing of the materials of the charge, so that a more rapid distilling process is attained than can be effected with 65 the muffle, tubular, or other furnaces. The products of the zinc distillation escape through the canal *p* into the condensing-chamber *o*, where the same are condensed and let off through the space *r*. The zinc-dust formed 70 during this process is caught in the vessel or chamber *q*, which, in consequence of its size, can be provided with one or more partitions. After continuing the process for about 75 six hours the zinc contained in the retort is distilled off and the residue is removed by the port *l*, which is for this purpose turned downward, whereupon the apparatus is so rotated that the port *l* is uppermost, a fresh charge introduced, and the process recommenced.

80 We are aware that rotary furnaces for treating ores are not new, and do not broadly claim such.

85 We claim as our invention—

1. The described apparatus, consisting of 90 the cylindrical shell having an opening in one end to admit the heating-blast and an opening in the other end for the exit of the vapors from the retort, said shell being supported on rollers and provided with cog-rings and pinions 95 for turning it and having radially-arranged channels leading from its interior outward, and an opening for the admission of the charge, in

combination with a retort, *e*, supported within the shell, with a space about it connected with the inlet-passage for the blast, a fixed collecting-canal arranged over the canals *h* and communicating therewith as the cylinder is turned, and a suitable discharge-passage from the collecting-canal, substantially as described.

2. The described apparatus, consisting of the cylindrical shell having an opening in one end to admit the heating-blast and an opening in the other end for the exit of the vapors from the retort, said shell being supported on rollers and provided with cog-rings and pinions for turning it and having radially-arranged channels leading from its interior outward, and an opening for the admission of the charge, in combination with a retort, *e*, supported within the shell, with a space about it connected with the inlet-passage for the blast, a fixed collecting-canal arranged over the canals *h* and communicating therewith as the cylinder is turned, and a suitable discharge-passage from the collecting-canal and also combined with a condensing-chamber, substantially as described.

3. The described apparatus, consisting of the

cylindrical shell having an opening in one end to admit the heating-blast and an opening in the other end for the exit of the vapors from the retort, said shell being supported on rollers and provided with cog-rings and pinions 30 for turning it and having radially-arranged channels leading from its interior outward, and an opening for the admission of the charge, in combination with a retort, *e*, supported within the shell, with a space about it connected with the inlet-passage for the blast, a fixed collecting-canal arranged over the canals *h* and communicating therewith as the cylinder is turned, and a suitable discharge-passage 35 from the collecting-canal and also combined 40 with a condensing-chamber, and a zinc-dust collector, substantially as described.

In testimony whereof we have signed this specification in the presence of two subscribing witnesses.

WILHELM RICHTER.
RUDOLF LORENZ.
